UNITED STATES PATENT OFFICE.

MICHAEL J. GRIFFIN, OF HARTFORD, CONNECTICUT.

HORSESHOE.

1,124,422.

Specification of Letters Patent.

Patented Jan. 12, 1915.

Application filed September 24, 1914. Serial No. 863,295.

To all whom it may concern:

Be it known that I, MICHAEL J. GRIFFIN, a citizen of the United States, residing at Hartford, in the county of Hartford and 5 State of Connecticut, have invented a new and Improved Horseshoe, of which the following is a specification.

My invention relates more especially to that class of horseshoes known as cushion 10 shoes, and an object of my invention among others, is to provide means for securely fastening the cushioning material in place.

One form of shoe embodying my invention and in the construction and use of 15 which the objects herein set out, as well as others, may be attained, is illustrated in the accompanying drawings, in which—

Figure 1 is a top plan view of a horseshoe embodying my invention, the disposition 20 of the cushioning material at the heel being illustrated in dotted outline. Fig. 2 is a detail view of a portion of a shoe illustrating the relative position of the fastening means before a cushion is secured in place. 25 Fig. 3 is a like view in section on plane denoted by dotted line 3—3 of Fig. 1, showing the relative arrangement of the fastening prongs when holding a cushion in place.

In the accompanying drawings the 30 numeral 5 denotes a shoe that may be formed from any suitable material and supplied with any desired means for securing it to the hoof of an animal, as herein shown nail holes 6 to receive nails being provided. 35 Heel extensions 7 project from the side parts of the shoe at the heel toward each other to an extent to leave an opening 8 between the adjacent ends of said projections. A strip of cushioning material 9 is 40 located in a groove 10 in the upper surface of the shoe, this groove extending entirely around the shoe and being of a width at the heel double that at the other portions of the shoe. This strip 9 has one end 11 45 located at one side of the shoe at the heel, and the strip extends across the heel to the point 12 where it is bent and then is extended entirely around the shoe to the point 13 where it is again bent, extending across the heel of the shoe to the point 14 where it 50 ends. In order to securely fasten this cushion in place I provide sets of prongs 15, each set consisting of two prongs oppositely disposed and preferably out of line 55 in the direction in which the prongs are

bent, that is, as herein shown they are out of line crosswise of the groove. These prongs are so formed that a space 16 is provided between them this space tapering from a wider dimension at the end of the 60 prongs to a narrower dimension at the base of the prongs. I also dispose the sets of prongs so that one or more of the members of one set will coöperate with one or more members of another set in holding the cushion 65 in place.

In operation the cushion, formed of some 70 tough flexible material, is placed at the mouth of the groove and is driven down upon the prongs, and the tapered form of the opening between the members of each 75 set will cause the prongs of each set to be bent away from each other, and as illustrated in Fig. 3 of the drawings. Likewise, the members on adjacent sides of two sets, in thus assuming an outwardly curved form, 80 as to their companion members, will, when viewed lengthwise of the packing, form a wedge shaped relationship as illustrated in Fig. 3, this wedge shaped form being 85 smaller at the top than at the bottom, so that the members of each set coöperate to prevent the cushion from being displaced, and members of different sets also coöperate to the same end.

While I have shown and described herein 90 a satisfactory arrangement of prongs for carrying out my ideas, these may be departed from to a greater or lesser degree and yet be within the spirit and intent of the invention.

It will be noted that the prongs in the 95 groove have opposite flat faces and that these flat faces extend in the direction of the length of the groove which is an effective way of facilitating the lateral flexure of the prongs or their bending crosswise of said groove. It should be noted that the points of the prongs extend short of the top plane 100 of the shoe which is a feature of importance in that in the first place these prongs do not penetrate completely the cushioning material of whatever character the same may be. In addition to this feature is the further 105 equally important point that the cushioning material itself when driven home into the groove bends down these prongs so as to spread the cushioning material laterally and substantially and solidly compress it into 110 the groove. I might make it clear when I

5 speak of the fact that the prongs do not completely penetrate the cushioning material that they do not extend entirely therethrough, by virtue of which the cushioning material is appreciably stronger owing to its imperforate exterior surface.

I claim—

10 1. A horseshoe having means for attachment to a hoof and containing a groove for cushioning material, and prongs disposed in a set rising from the bottom of said groove and arranged to present a wedge shaped space between them wider at the point than at the base of the prongs, said tapered 15 shaped space extending longitudinally of the groove.

20 2. A horseshoe having means for attachment to a hoof and provided with a groove to receive a cushioning material, and prongs disposed in sets lengthwise along said groove and rising from the bottom thereof, the members of each set being arranged to provide a tapered space wider at the point than at the base of the prongs, said tapered 25 space extending longitudinally of the groove.

30 3. A horseshoe having means for attachment to a hoof and provided with a groove to receive a cushioning material, and sets of prongs rising from the bottom of said groove, the members of each set being disposed to provide a space wider at the point than at the base of the prongs, and the sets being arranged one out of line with another 35 lengthwise of said groove.

40 4. A horseshoe having means for attachment to a hoof and containing a groove in its upper surface, prongs rising from the bottom of said groove and disposed in sets, the members of each set being arranged to provide a space between them wider at the point than at the base of the prongs, and the sets being arranged one out of line of another lengthwise of the groove, and a cushioning material forced on to the ends of said 45 prongs whereby the members of each set are forced apart at their points and the mem-

bers of different sets are forced toward a plane passing between the sets.

5 5. A horse shoe having a groove for cushioning material, and prongs in the groove having opposite flat faces which extend in the direction of the length of said groove to provide for flexure of said prongs crosswise of said groove. 50

6 6. A horse shoe having a groove for cushioning material, and prongs in the groove, the prongs being flexible transversely of the groove, and their points extending short of the top plane of the shoe. 60

7 7. A horse shoe having a groove for cushioning material, and prongs in the groove, the prongs having opposite flat faces and their points extending short of the top plane of the shoe. 65

8 8. A horse shoe having a groove to receive cushioning material, and sets of prongs rising from the bottom of said groove, the sets being out of line with each other lengthwise of the groove. 70

9 9. A horse shoe having a groove to receive cushioning material, and sets of prongs rising from the bottom of said groove, the sets being out of line with each other lengthwise of the groove and the prongs of each set being out of line with each other crosswise of the groove. 75

10 10. A horse shoe having a groove to receive cushioning material, and also having prongs in sets in the groove, the prongs of each set being out of line with each other transversely of the groove. 80

11 11. A horse shoe having a longitudinally extending groove to receive cushioning material, and a series of prongs in the groove between the side walls thereof, said prongs being bendable by and on the application of the cushioning material in a direction to clamp said cushioning material against the side walls of the groove. 85
